Fig. 4.

Fig. 11.

Fig. 12.

A detailed line drawing of a mechanical assembly, likely a wheel or gear assembly, featuring various numbered components. The drawing includes a central vertical shaft, two large circular components (30), and several smaller components labeled 29, 31, 32, 33, and 36. The numbers are handwritten-style.

UNITED STATES PATENT OFFICE.

GEORGE W. P. OVERMAN, OF NORFOLK, VIRGINIA.

LIFEBOAT HOLDING AND LAUNCHING MECHANISM.

Application filed October 6, 1925. Serial No. 60,825.

The invention relates to means for holding lifeboats on the decks of ships and for releasing the boats quickly and expeditiously for launching from the ship.

One of the objects of the invention is the provision of a novel means for holding the bilge and keel of the boat on the chocks, and for releasing the boat from the chocks.

Another object of the invention is the provision of means controlled by the means for holding the boat on the chocks and releasing it therefrom by which the gripe hooks which engage the sides of the boat are securely held while the boat is on the chocks and all of said gripe hooks are simultaneously released when the boat is released from the chocks.

Another object of the invention is the provision of means controlled by the boat-releasing means by which the boat cover is securely held in place on the boat while the boat is on the chocks, the means for holding the cover being released simultaneously with the boat-releasing means to enable removal of the cover preliminary to launching.

A further object of the invention is the provision of a boat holding and launching device operated simultaneously with a cover holding and releasing device so arranged that a single man is needed to release the boat for launching in contradistinction to the means ordinarily employed requiring a plurality of operators for expeditious launching of the boat in an emergency.

The invention will be described in detail hereinafter and will be found illustrated in the accompanying drawings in which—

Figure 1 is a side view of the inboard side of a lifeboat showing the boat held on the chocks,

Figure 2 is a bow end view of the boat on the chocks,

Figure 3, a transverse sectional view on a plane indicated by the line 3—3 of Figure 1,

Figure 4 is a similar view on a plane indicated by the line 4—4 of Figure 1,

Figure 5 is a plan view of the holding and releasing mechanism,

Figure 6 is a sectional detail of the keel locking mechanism on a plane indicated by the line 6—6 of Figure 1, showing the keel locked on the chocks,

Figure 7 is a view of the same part shown in Figure 6 showing the keel released in the act of launching the boat,

Figure 8 is a fragmental detail in plan of the parts shown in Figures 6 and 7, the parts shown in the position of Figure 6, the keel of the boat being omitted,

Figure 9 is a sectional detail on a plane indicated by the line 9—9 of Figure 1,

Figure 10 is a sectional detail on a plane indicated by the line 10—10 of Figure 5,

Figure 11, a sectional detail on the plane indicated by the line 11—11 of Figure 1,

Figure 12, a view in section on a plane indicated by the line 12—12 of Figure 11,

Figure 13, a detail plan view of the parts shown in Figures 11 and 12,

Figure 14, a detail plan view on the plane indicated by the line 14—14 of Figure 1,

Figure 15, a detail view in elevation of the parts shown in Figure 14,

Figure 16, a sectional detail on a plane indicated by the line 16—16 of Figure 15, and

Figure 17, is a detail sectional view on a plane indicated by the line 17—17 of Figure 1.

In the drawings similar reference characters will be used to designate corresponding parts throughout the several views.

The deck of a steamer is indicated at A, and B davits of the usual construction mounted on the steamer's deck and having the boat C swung therefrom by means of the tackle D, in the usual manner.

The chocks 1 to support the boat on the ship's deck are of the open outboard type, and provided with a rectangular notch 2 to seat the keel of the boat.

The keel of the boat is locked in the notch 2 by means of disks 3 provided with a notch 4 in each of the disks, said notch being as shown arranged above the center of the disk, and

said disk is secured to a short shaft 5 journaled in a plate 6 secured to the deck by means of an angular extension 7, said shaft being also journaled by means of an angular member 8 having its ends driven into the chocks 1. Each of the disks 3 is also provided with a gear face 9 that meshes with a gear face 10 on a mutilated disk 11 secured to the operating shaft 12.

It will be understood that when the parts are in the position shown in Figures 2, 3, and 6 that the boat keel will be held in the

notches 2 of the chocks 1. By rotation of the shaft 12, by the instrumentalities to be hereinafter described, the disk 3 will be rotated into the position shown in Figure 7, and that during such rotation the keel of the boat will be lifted slightly from engagement with the lower wall of the notch 2 and then moved outwardly away from the chocks 1 in a position ready for launching.

Shaft 12 is adapted to be actuated by hand by means of a lever bar 13 secured to one of its ends, usually the forward or bow end, and the means for locking the keel on the chocks and also for holding the other instrumentalities to be hereinafter described in a holding position, a length of cable is secured to one of the davits B as shown at 14 and provided with a ring 15 adapted to engage over the end of the lever bar 13 to prevent accidental movement thereof.

The hooks for engaging the side rails of the boat C are designated 15^a and each of said hooks has a flexible securing member secured thereto including a turn buckle 16 and a link 17 at its lower end. Each of said links 17 is adapted to be engaged by a spur hook member 18 pivotally secured between upstanding ears 19 on a plate 20 secured to the ship deck A, and connected by means of a rod 21 with a crank member 22 secured to the shaft 12 by means of set screw 23. Each of the crank members 22 has bifurcated ends 24 between which the ends of the rods 21 are pivoted.

In Figures 2, 3 and 9, the means for holding the boat gripe hooks 15 in engagement with the gunwale of the boat are shown in holding position, and in Figure 9 in a broken line position, the spur hooks 18 which secure the deck end of gripe hooks 15 are shown in a releasing position, it being understood that the parts are so arranged relatively to the shaft 12 that when the keel locking mechanism is in a position to lock the keel, as heretofore described, the hooks will also be held in position to securely hold the boat gripe hooks in position to clamp down the boat to chock rest, but when the shaft 12 is rotated to release the keel as hereinbefore described, the spur hooks will be moved into the position shown in broken lines in Figure 9 to release the gripe hooks for removal from the boat.

The spur hooks 18 are, as shown clearly in Figure 9, formed with their rear ends, to which the rods 21 are secured, with an extension 25 that seats on the plate 20 when the hooks are in an open position as shown in dotted lines to maintain the pivotal connection between the rods 21 and the spur hooks 18 above the center of the pivot of the spur hooks to insure ready operation of said hooks when they are to be moved into a locking position, or in other words to pre-

vent a dead center between the rods 21 and the pivot of the spur hooks. Also the rods 21 on the outboard side of the shaft 12 are curved or bent downwardly intermediate of their ends to prevent any possibility of the interference of the rods 21 with a successful operation of the boat in releasing and launching it.

The cover holding and releasing device will now be described. The usual boat cover is designated 26 and has an apron 27 extending around the sides of the boat, but open at its ends, as will be hereinafter more particularly described.

Secured to the apron 27 on each side of the boat and extending downwardly therefrom, are tabs 28 to each of which is secured a length of rope 29 having loosely mounted thereon a ring 30, the end of the rope being spliced in eye 38^a its opposite end passed through ring 30 and back through eyelet in the tab and tied as indicated in Figure 1 to form a flexible holding means for the sides of the cover. The rings 30 are held in clamping members secured to the deck A and comprising plates 31 having upwardly extending side flanges 32 formed with notches intermediate of their ends as shown at 33. Each of these clamping members is mounted directly under the shaft 12, and mounted on the shaft 12 by means of split collars 34 are U-shaped members 35 secured to the extended ends of said split collars 34 by means of nuts 36 engaging the threaded ends of said U-shaped members 35, this structure admitting of adjusting the U-shaped members 35 to properly function in holding the rings 30 in engagement with the clamping members as shown in Figures 11, 12 and 13. The rings 30 are shown in a held position in full lines in Figure 11, while in dotted lines in the same figure the U-shaped member 35 is shown in the position assumed by the shaft 12 when the boat is released as hereinbefore described, so that the rings 30 are released from engagement by the clamping members.

As before stated the apron 27 at the ends of the boat is open, and fitted on outboard side of the boat with eyelets 37 and the apron on the other side is provided with slits 38, this being shown more particularly in Figure 2 and also in Figure 15. 39 indicates a rod pivotally secured to a lug 40 on the lever bar 13 and 39^a another rod secured to a lug 40^a on an arm 41 secured to the shaft 12 at the end remote from the lever bar 13. When the boat is in a held position on the chocks 1 as shown in the drawings, the rods 39 and 39^a are run through links 42 extended through the slits 38, the rods being inside of the apron 27, and a length of rope 43 secured in the upper eyelets 37 at each end of the cover is laced through the links 42 and the lower eyelets 130

37 and then tied around the upper projecting ends of the rods 39 or 39^a as the case may be with half hitches as shown at 44.

It will be apparent from this structure 5 that when the shaft 12 is rotated as hereinbefore described to release the boat, the rods 39 and 39^a will be moved downwardly and their upper ends will disengage the knots 44 and the links 42 thus releasing the ends of 10 the cover from the ends of the boat, and the sides of the cover being simultaneously released, as hereinbefore described, the cover may then be easily removed from the boat 15 preliminary to launching.

15 What is claimed is:—

1. In a lifeboat holding and releasing device for ships, a boat cover holding and releasing mechanism comprising brackets adapted to be secured to the ship's deck, 20 holding elements secured to said cover and adapted to engage in said brackets, a shaft, arms on said shaft adapted in one position to retain said holding elements in said brackets, other arms on said shaft, rods pivotally secured to the arms, links loosely engaging said rods and extending through slits in the cover, and the ends of the cover secured by means of said links.

2. In a lifeboat holding and releasing device, chocks for supporting a lifeboat and having rectangular notches to receive the keel of the boat, disks journaled on the chocks and having rectangular notches to cooperate with the notches in the chocks to 35 hold the keel and boat on the chocks, and a shaft suitably journaled and geared to said disks to rotate them and release the keel from engagement with the chocks.

3. In a lifeboat holding and releasing device, chocks for supporting a lifeboat and having rectangular notches to receive the keel of the boat, disks journaled on the chocks and having rectangular notches to cooperate with the notches in the chocks to

hold the keel and the boat on the chocks, a 45 shaft suitably journaled, and operative connections between said shaft and the disks to hold the disks in keel engaging positions and to release the keel from the chocks.

4. In a lifeboat holding and releasing device, boat chocks open toward the outward part of a vessel, disks rotatably mounted on the chocks and notched to engage the keel of a lifeboat and hold it on the chocks, a 50 shaft journaled longitudinally of the lifeboat when on the chocks and actuatable from an end of the boat, said shaft being geared to the disks aforesaid to release the boat from the chocks and move it outwardly 55 thereof.

5. In a lifeboat holding and launching mechanism, an operating shaft adapted to be journaled in lifeboat supporting chocks, means actuatable by said shaft to hold and release a lifeboat, crank members on the 65 shaft, rods secured to the crank members, and spur hooks pivotally secured to the rods and adapted to engage boat gripe hooks, said crank members being actuated simultaneously with the boat holding and releasing 70 means to release the gripe hooks with release of the boat.

6. In a lifeboat holding and launching mechanism, an operating shaft for holding and releasing a lifeboat arranged longitudinally of the boat when in position on chocks, 75 notched disks arranged to engage the boat keel and hold the boat on the chocks, said shaft being geared to said notched disks, spur hooks adapted to be pivotally mounted 80 on a ship's deck and to engage gripe hooks engaging the side rails of the boat, and means operatively connecting said shaft and the spur hooks aforesaid to actuate them simultaneously with said disks to hold and 85 release the gripe hooks.

In testimony whereof I affix my signature.

GEORGE W. P. OVERMAN.
